UNITED STATES PATENT OFFICE.

AARON J. TYLER, OF ALBION, NEW YORK, ASSIGNOR TO E. C. COLE, OF SAME PLACE.

SAW-VISE.

SPECIFICATION forming part of Letters Patent No. 331,745, dated December 1, 1885.

Application filed September 22, 1885. Serial No. 177,832. (No model.)

To all whom it may concern:

Be it known that I, AARON J. TYLER, a citizen of the United States, residing at Albion, in the county of Orleans and State of New York, have invented certain new and useful Improvements in Saw-Vises, of which the following is a specification, reference being had therein to the accompanying drawings.

10 My invention relates to improvements in saw-vises, and is designed to produce a device for firmly holding a saw during the operation of filing, and for preventing vibration and noise incident to said operation.

15 In the drawings, Figure 1 represents a plan view of the device; Fig. 2, a side elevation; Fig. 3, a longitudinal section, and Fig. 4 a detail of the lever.

One of the saw-holding jaws A is formed 20 on the ends of the arms of a U-shaped frame, B, which is provided with perforated ears C, for the passage of screws by means of which the device is secured to a frame or buck. The frame B has a rearward continuation, D, provided with a central recess or slot. On the rear or curved portion of the frame B is formed a frame, E, also of general U shape, and having its arms F extending freely forward parallel to and slightly raised above the 25 said frame B for about two-thirds (more or less) of the distance from the rear or base of the frame B to the jaws A. The arms F are within the space occupied by the frame B. Pivoted to the forward ends of the said arms 30 F by a transverse bolt or rod, G, is a frame, H, in size and shape corresponding to the frame B and coinciding therewith, and carrying one of the jaws A. From the rear of the frame H projects an extension, I, with a bifurcated end, as shown, coinciding in position 35 to the continuation D in the frame B. Within the bifurcated end of the extension I is pivotally fulcrumed the lever K, having its shorter arm preferably at about a right angle 40 to its longer arm. The said shorter arm is pivotally connected to an arm, L, of about the same length, which in turn is pivoted in the recess of the continuation D. The shorter arm

of the lever and the arm L form a toggle-joint connection between the rear ends of the two frames, the longer arm of the lever acting as an operating-handle, and when the jaws are closed rests between the arms F, as is seen in Fig. 3.

As the joint straightens the jaws are closed, 55 pressing the saw between them and firmly holding it.

When the arms of the joint are in line, the parts of the vise are brought to such a tension as to abolish vibration and prevent the disagreeable noise or screeching incident to saw-filing. The non-vibration is due to the pivoting of the movable jaw and frame to the arms F, so that the movable and fixed jaws shall be coincident and support the jaws 65 equally, and not allow that leverage and non-equality of pressure that is likely to occur when the movable jaw has a central arm only to support and move it.

I claim—

1. A saw-vise consisting of the fixed U-shaped frame B, carrying a jaw formed at the ends of the said frame, a U-shaped frame, E, integrally attached to the base of the frame B and having upwardly-projecting arms F, 75 and a U-shaped jaw-carrying frame, H, of a size corresponding to that of the frame B and pivoted to the arms F, the whole operated substantially as specified.

2. A saw-vise consisting of a fixed U-shaped 80 jaw-carrying frame, B, a U-shaped frame, E, integral with the base of the fixed frame and having arms F, a U-shaped frame, H, carrying a jaw and pivoted to the arms F, and a toggle-joint connection consisting of a link, L, 85 pivoted to the base of the fixed jaw, and an angle-lever fulcrumed to the base of the frame H and pivotally connected by its shorter arm to the link L, substantially as specified.

In testimony whereof I affix my signature 90 in presence of two witnesses.

A. J. TYLER.

Witnesses:

CLARENCE TYLER,
EDWARD C. COLE.
